UNITED STATES PATENT OFFICE.

WILLIAM H. MINER, OF CHAZY, NEW YORK, AND JOHN F. O'CONNOR, OF CHICAGO,
ILLINOIS; SAID O'CONNOR ASSIGNOR TO SAID MINER.

RAILWAY DRAFT-RIGGING.

1,391,067.

Specification of Letters Patent. Patented Sept. 20, 1921.

Application filed March 15, 1920. Serial No. 365,798.

To all whom it may concern:

Be it known that we, WILLIAM H. MINER and JOHN F. O'CONNOR, citizens of the United States, residing at Chazy, Clinton county, New York, and Chicago, Cook county, Illinois, respectively, have invented a certain new and useful Improvement in Railway Draft-Riggings, of which the following is a full, clear, concise, and exact description, 10 reference being had to the accompanying drawings, forming a part of this specification.

This invention relates to improvements in railway draft riggings.

15 The object of the invention is to provide an economical friction draft rigging for railway cars wherein the usual space between the sills is utilized for the friction elements proper and the spring resistances are 20 disposed outside of the sills in space not now usually occupied.

In the drawing forming a part of this specification, Figure 1 is a horizontal longitudinal sectional view of a portion of a railway draft rigging showing our improvements employed in connection therewith. Fig. 2 is a vertical transverse sectional view taken substantially on the line 2—2 of Fig. 1. And Fig. 3 is a detail perspective of one 30 of the movable friction elements.

In said drawing 10—10 denote channel shaped center or draft sills of a railway car arranged in a well known manner. Secured to the inner faces of said sills are stop castings or cheek plates each designated by the reference A. Each of said castings A provides a front stop shoulder 11 and a rear stop shoulder 12 as clearly indicated in Fig. 1. A more detailed description of said castings A will be found hereinafter. A portion 40 of a drawbar is indicated at 13, the same being operatively associated with the shock absorbing mechanism by means of a yoke 14 of well known form. In carrying out our 45 invention, we employ a front follower 15, rear follower 16, a pair of laterally movable friction elements 17—17, laterally arranged springs 18, loops 19, links 20 and stationary inclines formed on the castings A, herein- 50 after described.

Each of said castings A is formed with two substantially triangular formations at their centers which extend inwardly toward the center line of the gear, said triangular

formations providing a parallelly arranged 55 pair of rearwardly and inwardly directed inclines or friction surfaces 21—21 and a corresponding pair of forwardly and inwardly directed inclines or friction surfaces 22—22.

Each friction shoe 17 is provided with two sets of inclined or wedge friction surfaces 121—121 and 122—122 adapted to coöperate respectively with the inclines 21 and 22. The shoes 17 are formed at their ends with 65 flat transversely extending friction surfaces 23—23 which are adapted to coöperate with the inner faces of the followers 15 and 16.

The shoes 17 are centrally slotted as indicated at 24 to accommodate the links 20, 70 the latter being secured to the corresponding shoes 17 by heavy pins 25, the heads of which are preferably counter-sunk within the shoes so as to avoid any obstruction as the shoes move laterally toward each other 75 within the arms of the yoke 14. The links 20 pass outwardly through suitable slots in the castings A and sills 10 and at their outer ends are pivotally connected to slideable blocks 29 by means of heavy pivot pins 30. 80 The loops 19 are also pivotally connected to said blocks 29 by the same pins 30 as clearly indicated in Fig. 2.

The blocks 29 are slidably guided within U-shaped stirrup plates 31 which form fixed 85 bearings for the inner ends of the springs 18. It will be noted from an inspection of Fig. 2 that the loops 19 straddle the stirrup plates 31 so that said plates 31 assist in properly sustaining the loops and springs. 90 Preferably, separable followers 32 are employed at the outer ends of the springs 18 within the loops 19, said followers 32 having suitable projections 33—33 to straddle the loop and maintain the followers in 95 proper position.

From an inspection of Fig. 1, it will be noted that the followers 15 and 16 are normally spaced from the respective stops 11 and 12 a distance corresponding to the permissible movement of the draft rigging. Also, it will be seen that the shoes 17 are in their outermost position, that is, are separated the maximum amount. In operation, and assuming a buffing or inward movement 100 of the drawbar, it is evident that both followers 15 and 16 will move rearwardly simultaneously and uniformly with the

shoes 17. As the latter move rearwardly they will slide up the inclines 21—21 and thereby be forced inwardly toward each other. This generates friction between the 5 surfaces 21 and 121 and also between the ends of the shoes 17 and the follower 15. During this movement, the links 20 will be pulled inwardly and also swung slightly toward the rear so that the blocks 29 will be 10 pulled inwardly within the stirrup plates 31 and the springs compressed by means of the loops 19. The limit of movement is obtained when the rear follower 16 engages the rear stops 12. Upon removal of the actuating 15 pressure, the expansion of the springs 18 will re-act through the loops 19 and links 20 to return the shoes 17 to their normal position.

Various changes and modifications may 20 be made in the details of construction and arrangement of parts without departing from the spirit of our invention and all such changes and modifications are contemplated as come within the scope of the claims appended hereto.

We claim:

1. In a railway draft rigging the combination with draft sills having stationary sets of inclines on their inner faces; of laterally inward and longitudinally movable friction shoes coöperable with said inclines; spring resistances disposed outside of the sills; connecting means between said spring resistances and shoes; followers at the ends of said shoes in engagement therewith; and stops with which said followers are adapted to coöperate.

2. In a railway draft rigging, the combination with draft sills having oppositely extending sets of stationary inclines on their inner faces; of laterally inwardly and longitudinally movable friction shoes coöperable with said inclines; means for actuating said shoes; laterally extending springs on the outer sides of said sills; loops inclosing said springs; and link connections between the shoes and the loops.

3. In a railway draft rigging, the combination with draft sills each provided on its inner face with oppositely extending pairs of parallel inclined friction surfaces; a pair of friction shoes, each of said shoes being provided on its outer side with oppositely inclined pairs of parallel friction surfaces 50 coöperable with said stationary inclines; followers at the ends of said shoes, the followers being simultaneously movable; spring resistances disposed outside of the

sills; and operative connections between the spring resistances and said shoes.

4. In a railway draft rigging, the combination with a drawbar, yoke, and front and rear followers; of draft sills; laterally extending springs on the outer sides of said sills; friction shoes disposed between the 65 sills and between said followers, said shoes being laterally and longitudinally movable; operative connections between said shoes and springs adapted to compress the latter upon actuation of the shoes; and stationary 70 means having inclines, said shoes being provided with coöperating inclined faces.

5. In a railway draft rigging, the combination with a drawbar, yoke, and front and rear followers; of draft sills; laterally extending springs on the outer sides of said sills; friction shoes disposed between the sills and between said followers, said shoes being laterally and longitudinally movable; operative connections between said shoes 75 and springs adapted to compress the latter upon actuation of the shoes; and stationary means having inclines, said shoes being provided with coöperating inclined faces, said stationary means being provided also with 80 stop shoulders normally spaced from the followers and adapted to limit the movements of the latter.

6. In a railway draft rigging, the combination with draft sills; of stop castings 90 secured to the inner faces of said sills, each of said stop castings having front and rear stop shoulders and opposed sets of inclines formed integrally therewith intermediate the stop shoulders; a drawbar; yoke-acting 95 means; front and rear followers; friction shoes having their ends in engagement with the followers and provided with inclined faces coöperable with said stationary inclines; laterally arranged springs disposed 100 outside of the sills; fixed bearings for the inner ends of said springs; members encircling said springs; and link connections between said members and said friction shoes, said followers being normally spaced 105 from the stop shoulders and the latter adapted to limit the movement of the mechanism.

In witness that we claim the foregoing we have hereunto subscribed our names this 110 21st day of February, A. D. 1920.

WILLIAM H. MINER.
JOHN F. O'CONNOR.
